CLAIM

I claim the ornamental design for a barrier for shelf pusher system, as shown and described.

DESCRIPTION

FIG. 1 is a front perspective view of a barrier for shelf pusher system, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view.

The article is shown with a symbolic break in its length. The appearance of any portion of the article between the wavy break lines forms no part of the claimed design.
